US00D641878S

(12) **United States Design Patent**
Anitua Aldecoa

(10) **Patent No.:** **US D641,878 S**
(45) **Date of Patent:** **** Jul. 19, 2011**

(54) **ANGULATED ABUTMENT**

(75) Inventor: **Eduardo Anitua Aldecoa**, Alava (ES)

(73) Assignee: **Biotechnology Institute, I Mas D, S.L.**,
Alava (ES)

(**) Term: **14 Years**

(21) Appl. No.: **29/358,044**

(22) Filed: **Mar. 22, 2010**

(30) **Foreign Application Priority Data**

Sep. 21, 2009 (EM) 001166086

(51) **LOC (9) Cl.** **24-03**

(52) **U.S. Cl.** **D24/156**

(58) **Field of Classification Search** D24/155-156,
D24/176, 180; D8/387-388; 606/304, 74;
433/125-126, 172-176

See application file for complete search history.

(57) **CLAIM**

The ornamental design for an angulated abutment, as shown and described.

DESCRIPTION

FIG. 1 is a top perspective view of the abutment according to the claimed design;

FIG. 2 is a bottom perspective view of the abutment according to the claimed design;

FIG. 3 is a front view of the abutment according to the claimed design;

FIG. 4 is a rear view of the abutment according to the claimed design;

FIG. 5 is an enlarged top view of the abutment according to the claimed design;

FIG. 6 is an enlarged bottom view of the abutment according to the claimed design; and,

FIG. 7 is a side view of the abutment according to the claimed design.
